UNITED STATES PATENT OFFICE.

JEROME R. GEORGE, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

CONVEYING MECHANISM.

Application filed March 18, 1921. Serial No. 453,411.

To all whom it may concern:

Be it known that I, JEROME R. GEORGE, a citizen of the United States, residing at Worcester, in the county of Worcester and 5 Commonwealth of Massachusetts, have invented a new and useful Improvement in a Conveying Mechanism, of which the following, together with the accompanying drawings, is a specification.

10 The present invention relates to conveying mechanism, and more particularly to such mechanism as is used for handling the product of a rolling mill. The invention contemplates improvements in the construction 15 and operation of the conveying devices which constitute the so-called connecting table and broadside transfer in a rolling mill plant, for the purpose of facilitating the longitudinal and also the broadside movement 20 of the rolled product.

Other and further objects of the invention will appear in the following description, reference being had to the accompanying drawings, in which—

25 Fig. 1 is a diagrammatic plan view of rolling mill apparatus, showing the adaptation of the invention thereto.

Fig. 2 is a sectional view on an enlarged scale, the section being taken on the line 30 2—2 of Fig. 1.

Fig. 3 is an enlarged view, in elevation, of one of the elements of the conveying mechanism.

Like reference characters refer to like 35 parts in the different figures.

Referring first to Fig. 1, there is indicated diagrammatically a plurality of stands of reducing rolls 1, 1, the same constituting, for purposes of illustration, a continuous 40 rolling mill of any known type equipped with a run-out table, shown here as consisting of conveyor rolls 1', 1'. In substantial alinement with the above mill and its run-out, and separated therefrom by a considerable distance, there is shown a second 45 rolling mill, the same being constituted by a plurality of reducing rolls 2, 2, for the further reduction of the product that emerges from the rolls 1, 1 of the first mill. Interposed between the rolls 1, 1 and the rolls 2, 2, in the manner well known in apparatus of this class, is a connecting table adapted to procure the longitudinal movement of the stock from the first set of reducing rolls

1, 1 to the second set of reducing rolls 2, 2. 55

According to the usual practice, a connecting table provides a series of ordinary cylindrical conveying rolls having on one side thereof a set of longitudinal guides or guards, the latter serving to prevent movement of the stock off the rolls. Obviously, with the use of such side guards, it is possible to shift the stock broadside from the rolls of the connecting table in one direction only, and this is a serious limitation on the 60 flexibility and range of usefulness of the apparatus. According to the present invention this difficulty is overcome, by the provision of a connecting table in which the conveying devices operate automatically, in 65 the absence of any side guards, to retain the stock thereon, and at the same time permit the sidewise transfer of the stock in either direction.

For the purpose of illustrating this capability of operation, the connecting table of the present invention, consisting of rolls 3, 3 of a special construction, as hereinafter described, is shown in Figs. 1 and 2 in operative relation to sets of ordinary conveyor 75 rolls 4, 4 and 5, 5, the same being arranged parallel to, and on opposite sides of the run-out and connecting table. The rolls 4, 4 may be arranged to deliver material for instance, to another rolling mill, as indicated by the 80 reducing rolls 6, 6, while the rolls 5, 5 may be arranged to deliver material to other 85 operating mechanism, such as a shear 7 or the like. It is contemplated, by the present 90 invention, that the stock that is run out on the connecting table shall, as desired, be forwarded longitudinally to the reducing 95 rolls 2, 2, or transferred broadside in either direction to the conveyor rolls 4 or the conveyor rolls 5; the instrumentalities which permit of this selective operation will now be described in detail.

Referring to Fig. 3, each roll 3 of the connecting table is shown as comprising opposite frusto-conical portions 8, 8, preferably 100 having between them a peripheral groove 9; at their larger and outer ends these frusto-conical portions are bevelled off, as shown at 10, 10, Fig. 3, in order to facilitate the broadside movement of the stock, either 105 onto or off of the rolls 3, 3. Between said rolls 3, 3 and the conveyor rolls 4, 4 and 5, 5 on opposite sides of the connecting table,

extend a plurality of fixed transverse skids 11, 11, which support the stock in its broad-side movement. This broadside movement across the skids 11, 11 is effected in any 5 suitable way, as by the use of chains 12, 12 passing over pulleys 13, 13 and carrying bevelled dogs 14, 14 that engage the stock from either side edgewise at a plurality of points.

10 The operation of the mechanism is as follows:—Because of the construction of the rolls 3, 3 of the connecting table, the stock, as delivered thereto by the run-out 1', is carried forward longitudinally upon said 15 rolls, without any tendency to deflect side- wise, even in the absence of restraining devices or side-guards. The angle of inclination of the opposing frustro-conical surfaces 8, 8 is such as to prevent upward or outward 20 travel of the moving stock; in other words, this inclination is at or above the angle of sliding or moving friction, with the result that any tendency of the stock to shift trans- versely on the rolls 3, 3 is always in an 25 inward direction.

For positively procuring this inward shifting, as where the stock is delivered to the connecting table more or less out of line with the longitudinal center thereof, it is 30 proposed to produce relative movement or slipping between the rolls 3, 3 and the conveyed material. This may be accomplished, for example, by operating said rolls 3, 3 at a peripheral speed different from that of the rolls 1', 1' through proper speed control 35 of the motors 15 and 16 which drive the rolls 3, 3 and 1', 1', respectively; the same effect can be produced, obviously, by inter- posing an obstruction to the movement of 40 the material by the rolls 3, 3. In the case of square bars, as shown in Fig. 3, the central grooves 9, 9 assist not only in main- taining the stock straight and true, but also 45 serve to carry such bars on edge, so that they may readily enter a "diamond" pass, as provided, along with the other usual forms of passes, in the rolls 2, 2.

In the absence of side guards or restraining devices of any character, the alined dogs 50 14, 14 of the chains 12, 12 can engage and move the stock transversely in either direction, transferring it at will from the connecting table, either to the conveyor rolls 4, 4 or to the conveyor rolls 5, 5; or if de- 55 sired for any purpose, as indicated in Fig. 2, returning the stock from the conveyor rolls to the connecting table, or carrying it clear across the connecting table to the other set of conveyor rolls.

60 While the invention is here shown and described in connection with a definite arrange-

ment of rolling mill apparatus, it is to be understood that such use of the same is not obligatory, but is adapted merely for purposes of illustration; it is desired therefore 65 that only such limitations be imposed upon the invention as are set forth in the appended claims.

I claim:

1. In rolling mill apparatus, a connecting 70 table consisting of a series of alined conveyor rolls, each providing supporting sur- faces oppositely inclined from and extend- ing substantially at right angles to the nor- mal central position of the stock in its longi- 75 tudinal travel on said rolls, the angle of in- clination of said supporting surfaces being at or above the angle of sliding or moving friction and means for imparting to said rolls a surface speed different from the linear 80 speed at which the stock is delivered thereto, whereby, in consequence of the slippage thus produced, said stock will seek the bottom of the incline afforded by said supporting 85 surfaces. 85

2. In apparatus of the class described, the 90 combination with the conveyor rolls of a rolling mill run-out, of a connecting table pro- viding rolls having oppositely inclined 95 surfaces, and means for operating said last named rolls at a peripheral speed different from that of said conveyor rolls thereby to produce slippage of the conveyed stock, and its inward shifting on the inclined sup- porting surfaces of said connecting table 95 rolls. 95

3. In apparatus of the class described, the 100 combination with the conveyor rolls of a rolling mill run-out, of a connecting table con- sisting of a series of alined conveyor rolls, each providing supporting surfaces oppo- sitely inclined from and extending substan- tially at right angles to the normal line of 105 movement of the stock on said rolls, and means for operating the connecting table rolls at a peripheral speed different from that of said run-out rolls thereby to produce slippage of the conveyed stock and its in- 110 ward shifting on the inclined supporting surfaces of said connecting table rolls. 110

4. In apparatus of the class described, a 115 series of conveying rolls, each consisting of opposed frustro-conical portions inclined toward the center thereof, with a peripheral groove between said opposed portions, and means for causing broadside movement of the stock onto and off of said rolls in either direction, said means comprising movable dogs having their engaging edges inclined.

Dated March 11, 1921.

JEROME R. GEORGE.
